UNITED STATES PATENT OFFICE

99,990

DESIGN FOR LEATHER OR SIMILAR ARTICLE

Nathan Brezner, Newton, Mass.

Application September 7, 1935, Serial No. 58,468

Term of patent 7 years

To all whom it may concern:

Be it known that I, Nathan Brezner, a citizen of the United States of America, residing at Newton, in the county of Middlesex and Commonwealth of Massachusetts, have invented a new, original, and ornamental Design for Leather or Similar Article, of which the following is a specification, reference being had to the accompanying drawing, forming a part thereof.

The figure is a plan view of a piece of leather showing my new design.

The characteristic feature of the design is a plurality of parallel stripes each consisting of

a series of sinuous or wavy bars with shorter substantially straight cross-bars disposed substantially perpendicular to the length thereof and extending in opposite directions from their respective ends, the sinuous bars of adjacent stripes sloping in the same direction.

I claim:

The ornamental design for leather or similar article substantially as shown and described.

Signed by me at Boston, in the county of Suffolk and Commonwealth of Massachusetts, this 6th day of September, 1935.

NATHAN BREZNER.
